CLOTHESPIN

James D. Tinsley, Bakersfield, Calif.

Application March 4, 1947, Serial No. 732,261

5 Claims. (Cl. 24—137)

1

My invention relates to clothes pins, particularly to a composite wood and wire device adjustably adapted to releasably engage fabrics of different thicknesses when hung over clothes lines.

It is a principal object of my invention to provide a clothes pin in which a wooden block and a wire spring cooperate to make the said pin adjustable to receive and engage fabrics of different thicknesses.

It is an important object of my invention to provide a clothes pin of the character described in which the wooden block is formed substantially as a right prism and the spring is mounted thereon eccentric to each of the axes thereof to be adjustable to yieldingly grip each of the lateral faces thereof with a different degree of pressure.

It is a further object of my invention to provide a clothes pin of the character described in which the wooden block is slidable upon a dependent portion of said spring to aid in disengaging fabrics held thereby.

It is a still further object of my invention to provide a clothes pin of the character described which is relatively simple and cheap to manufacture, easy to use, long-lasting and efficient in use, and which cannot get out of order unless tampered with.

Other objects and advantages of my invention will become apparent during the course of the following specification, in which like numerals are used to designate like parts throughout the specification and drawings.

In the drawings:

Figure 1 is a top plan of a clothes pin embodying my invention.

Figure 2 is a side elevational view of the clothes pin, illustrating the relation of the block and wire spring.

Figure 3 is another side view of the same, illustrating the eccentric relation of one of the dependent arms to the block.

Figure 4 is a top plan somewhat similar to Figure 1, the spring being shown in the plurality of positions it may assume relative to the block.

Figure 5 is a side elevation of a modification of the clothes pin in which the dependent arm of the spring passing through the block is lengthened relative to the other arm.

Figure 6 is a view of the pin illustrated in Figure 5, the block being shown translated downward on the lengthened arm, and

Figure 7 is a transverse section of another modification of the clothes pin, the arm engaging the block being shortened, to engage in annular grooves formed internally of the block.

2

Referring now in detail to the drawings, particularly to Figures 1-4, the numeral 10 designates a block, preferably of wood, in the form of a right prism having chamfered edges, as at 11, surrounding it at top and bottom. The ends of the block are, of course, square, but the body may be cubical or elongated as shown. The block is provided with a longitudinal bore 12 eccentric to both of the major horizontal axes of the prism.

10 A spring 13, formed of a single wire, is made by bending the wire intermediate its ends to form a helical middle portion 14 of at least two coils, the respective end portions of the wire being extended tangentially to the circumferences of the end coils to form a right comprising the spring 13 and two oppositely extending divergent arms 15 and 16. A portion 17 of arm 15 extends across the top of the block 10 approximately one-half the width of the said block, the arm 15 being then bent at right angles to the portion 17 and passed through the eccentric bore 12, a loop 18, adapted to press against the bottom surface of the said block, being formed at the lower end. The other arm 16 springs a relatively short distance beyond the plane in which lies one of the lateral sides 19, where it is bent downward at an angle slightly less than a right angle, the dependent portion 20 being adapted to yieldingly grip the dependent side closely adjacent the lower chamfered edge thereof. The gripping force will be commensurate with the strength of the wire, the angle of the bend, and the position of the arm relative to the eccentric bore, as is shown in Figure 4, and will be hereinafter explained, but best results will be obtained if the lateral side farthest removed from the said eccentric bore is chosen in making this bend. The dependent portion 20 is extended downward below the bottom of the block, as shown in Figure 2, and a loop 21 providing a finger piece 40 for moving the arm 20 outwardly relative to the block 10 is formed on the end.

The obvious purpose of any clothes pin is to yieldingly grasp fabrics hanging on a clothes line to hold them thereon against the action of wind 45 or other conditions which would tend to blow them away or from the clothes line. In using my improved clothes pin, the hanging fabric is gripped between the yielding dependent arm 20 and one of the lateral sides 19. When the clothes pin is pressed downward on the fabric, the arm 20 is forced outward, securely holding the fabric through the energy of the spring against the block. When the fabric is to be removed from the clothes line, the block is lifted upward, the 55 released energy of the arm 20 returning it to the position shown in Figure 2. In case the pin is

dropped to the ground during the placing or removal, my pin has the additional advantage of not rolling away, but will be found directly under the place from which it was dropped.

In using any of the known pins of the prior art, whether of wood, metal or wire, the pin has a substantially fixed tensile adjustment which will ordinarily secure 75 per cent of the fabrics to be hung on clothes lines satisfactorily. However, it is sometimes necessary to hang fabrics which fall into the other 25 per cent, for example, heavy clothing, rugs, quilts, or fabrics having hemmed edges thicker than the rest of the fabric. In such cases, the pin must be sprung to provide a wider gripping opening. In the case of the all-wood pin, breakage is a common occurrence, while in the case of metal or wire pins, the increased pressure against the spring or metal may damage the fabric, and frequent use of such pins with thick articles has a tendency to weaken the spring and destroy its resiliency, so that when next used with the 75 per cent of fabrics to be hung, it will have lost its grip, making it useless. I have overcome this difficulty in my arrangement of my spring in an eccentric bore.

The 75 per cent of all fabrics to be hung will be held securely and without damage in the arrangement of spring 13 shown in Figures 1, 2, and 3, and in the solid line representation of the spring in Figure 4. Since the bore 12 is eccentric to both major horizontal axes, it is obvious that a different gripping tension between spring and lateral sidewall is obtainable on each of the said lateral walls or sides as the dependent arm 22 is rotated in the bore. The adjustment is made quickly and easily by moving the other dependent arm 20 outwardly by means of the finger piece 21 until the said arm is perpendicular, whereupon the spring 13 may be rotated about the block 10, clearing the respective corners thereof because of their chamfered edges, until the dependent arm 20 is in a position best adapted to hold the particular article hanging on the clothes line, as shown clearly in Figure 4.

In the modification of Figures 5 and 6, the spring 13 is formed in the same manner already described, except that the divergent arm 15 carries a dependent arm 23, corresponding functionally and otherwise to the arm 22 of Figures 1-4, is considerably longer, the extension of said arm 23 being sufficient to allow the block 10 to slide downward far enough to clear the loop 21 of the dependent portion or arm 20' carried by the other divergent arm 16, as shown in Figure 6. This embodiment has all of the advantages already pointed out, plus the additional advantage of permitting easier adjustment of the spring relative to the different sides, making the removal of fabrics from the grip of the arm 20 easier, and in instances where such an arrangement is desirable in order to avoid contact of the fabric with the clothes line, permitting hanging the pin directly on a clothes line 24, as shown in Figure 6, and holding the article between the block 10 which has been lowered on the arm 23 and the arm 20.

In the modification of Figure 7, an eccentric apertured bore 25 is substituted for the through bore 12, annular grooves 26 being formed in the block 30 in one or two places along the length of the apertured bore 25 to engage humps 27 formed on the shortened dependent arm 28 carried by the divergent arm 15, the arm 28 being substituted for the dependent arm 22 of Figures 1-4, and arm 23 of Figures 5 and 6, thus effecting a saving of spring material and eliminating the outwardly

extending loop 18. The other divergents arm 16 is provided with a dependent arm 31 which carries a loop 32, the arm 31 and loop 32 being similar to the arm 20 and loop 21 of Figures 1 to 4, inclusive, and to arm 20' and loop 21' of Figures 5 and 6.

I have described my invention in the different embodiments best known to me at this time. It is to be understood, however, that changes in the shape and arrangement of my invention may be made without departing from the spirit of the invention within the scope of the subjoined claims.

Having thus described my invention, I claim:

1. An improved clothes pin comprising a block formed as a right prism formed with a vertically extending bore therein, the said bore being disposed eccentric to each major horizontal axis of said block, and a spring formed of a single piece of wire and having spaced apart coplanar dependent arms, one of said arms being disposed in said eccentric bore and the other said arm being adapted to yieldingly grip a selected one of the lateral faces of said prism.

2. An improved clothes pin comprising a member having the form of a right prism, said prism being formed with a vertical bore extending therethrough disposed eccentrically to both major horizontal axes of said prism, and a spring member formed from a single wire coiled intermediate its ends, the end coils being extended tangentially to the circumference thereof to form a pair of oppositely extending arms, one of the said arms being bent adjacent said coils and disposed in said vertical bore and secured against upward translative movement relative thereto, the other said arm being bent at an angle less than 90 degrees outwardly of said prism to lie in a substantial vertical plane passing through said first mentioned arm and being adapted to yieldingly grip a selected one of the respective lateral faces of said prism when the said spring member is rotated about the periphery of said prism on a pivot formed by said first mentioned arm, to yieldingly grip articles of varying thicknesses between the said last mentioned arm and the respective lateral faces of said prism.

3. An improved clothes pin comprising a member having the form of a right prism, said prism being formed with a vertical bore extending therethrough disposed eccentrically to vertical planes passing through said prism along the major horizontal axes thereof, and a spring member coiled intermediate its ends, the said coils being arranged to rest on one of the bases of said prism, the end coils being extended tangentially to the respective circumferences thereof to form oppositely extending arms, the said first arm being bent normal to said extension to be disposed in said bore and extend therethrough a distance slightly greater than the height of said prism and having means on the end thereof to arrest downward translative movement of said prism on said arm, the second arm being disposed on said base to extend outwardly thereof a short distance and being thereupon bent downward at an angle less than 90 degrees to lie in a perpendicular plane passing through said first arm and adapted to yieldingly grip the respective lateral faces of said prism successively when said spring member is rotated about said prism on a pivot formed by said first arm, the said prism being adapted for translative movement up and down on said first arm.

4. An improved clothes pin comprising a mem-

ber having the form of a right prism, said prism being formed with an apertured bore extending longitudinally into said prism from one of the bases thereof and said bore being formed with at least one annular groove surrounding said apertured bore, and a spring member coiled intermediate its ends, the coils being adapted to rest on the prism base adjacent the opening of said bore, the end coils being extended tangentially to the respective circumferences thereof to form oppositely extending arms, the first said arm being bent normal to said extension and disposed in said apertured bore, there being at least one hump formed in said arm adapted to engage in the annular groove formed in said prism surrounding said bore to secure said first arm therein, the second said arm being disposed on said base to extend outwardly thereof and be bent downward at an angle less than 90 degrees to lie in a perpendicular plane passing through said first arm and yieldingly grip one of the lateral faces of said prism, the said second arm being adapted to successively grip each of the said lateral faces of said prism with different degrees of pressure when the said spring member is rotated about the said prism on a pivot formed by said first arm.

5. An improved clothes pin, comprising a right prism, said prism being formed with a vertically-

extending bore therethrough, said bore being disposed eccentrically to both major horizontal axes of said prism, a spring member comprising a single length of wire, said spring member being formed to provide a bight and a pair of depending arms, one of said arms being pivotally mounted in said bore, said other arm being inwardly disposed toward said first arm at an angle less than ninety degrees relative to said bight, said second-named arm being adapted to yieldingly grip a selected one of the respective lateral faces of said prism when said spring member is rotated about the periphery of said prism on said first arm, whereby to provide means for yieldingly gripping articles of varying thicknesses between said last-named arm and the respective lateral faces of said prism.
